UNITED STATES PATENT OFFICE.

GEORGE W. COFFIN, OF LYNN, MASSACHUSETTS, ASSIGNOR OF THREE-FIFTHS TO HERMAN BEHR, OF NEW YORK, N. Y.

ABRADING AND POLISHING MACHINE FOR BOOTS AND SHOES.

SPECIFICATION forming part of Letters Patent No. 274,440, dated March 20, 1883.

Application filed February 4, 1882. (Model.)

To all whom it may concern:

Be it known that I, GEORGE W. COFFIN, a citizen of the United States, residing at Lynn, in the county of Essex and Commonwealth of Massachusetts, have invented certain new and useful Improvements in Mechanism for Abrading and Cleaning or Polishing the Soles of Boots and Shoes, of which the following, taken in connection with the accompanying drawings, is a specification.

The invention relates to mechanism for abrading and cleaning or polishing the soles of boots or shoes. It is specially adapted to operate upon the face of the sole; and it consists in the peculiar construction and arrangement and the various combinations of the operative parts, all substantially as described.

In the accompanying drawings, Figure 1 is a plan view of the entire machine. Fig. 2 is a side elevation of the machine, made partly in section. Fig. 3 shows the opposite side elevation of the entire machine. Fig. 4 is a perspective view of the abrasive tool. Fig. 5 shows a sectional view of said tool attached to its carrying-shaft.

Upon the column A is a hollow shell or casing, B, which is provided with an exhaust-pipe, C, and also a hollow arm, D, at the end of which rod is a bonnet, G, adapted to receive the cleaning-brush E, and on the top of the arm D is a horn, F, that reaches upward toward the abrasive tool, as shown in Figs. 2 and 3.

The end shell or casing, B, is composed of two annular chambered plates, attached together in the usual manner, so as to form an interior chamber suitable for the reception of an exhaust-wheel.

The wheel is and may be of any usual construction common to exhaust-fans, so that it will draw a strong current of air through the horn F and arm D, in the direction of the arrows thereon, into the center of the said casing B. The air and leather dust are sucked into the horn, and are by the operation of the fan discharged from the casing B through the exhaust-pipe C.

The shaft a of the fan has at one end a pulley, e, which is connected by belt b with a driving-pulley, d, through which means the fan is made to revolve. Said pulley d is fixed

on one end of a shaft, f, that, extending through the column a, carries on its opposite end the pulleys h, i, k, and m. The pulleys h and i are designed to receive the driving-power of the machine, and are arranged one fast, the other loose, in the usual manner, for that purpose. The pulley m connects by the belt n with the pulley p, so as to revolve the pulley p on its journal-pin q. Said pulley p is provided with a wrist-pin, r, to which is attached one end of a rod, S, the opposite end of which is jointed to the carrier-arm t. Said carrier-arm t is journaled on a pin, w, that projects from the arm D, and has in its opposite end a hole or socket adapted to receive the shank or tang of the finishing-brush. Said brush is retained in connection with the carrier-arm t by means of the pin W, and is caused to vibrate in an obvious manner by each revolution of the pulley p.

Extending upward from the casing B are two vertical ears, 3 and 4, in which is journaled a horizontal shaft, 5. Said shaft 5 carries a fixed plate, 6, and two fixed pulleys, 7 and 8. Motion is imparted to the shaft by belt 9, that connects the pulleys 7 and k. The pulley 8 connects by belt 10 with a pulley, H, fixed upon one end of a horizontal shaft, 12, that is journaled in the end of the arms. Said shaft 12 carries a cleaning-brush, E, which is arranged upon the shaft and in reference to the bonnet G, as shown in Figs. 2 and 3. Motion is imparted to the brush from the pulley 8 in an obvious manner.

The face-plate 6 is provided with a wrist-pin that receives one end of a connecting-rod, 14, the opposite end of which rod is pivoted to the crank-arm 15. Said crank is arranged to turn in the end of a bracket-arm, 16, as shown in Figs. 2 and 3. Said crank is reciprocated by each revolution of the face-plate 6, and is provided with a hole or socket in its bottom end to receive the shank or tang of the abrasive tool, which thereby receives a vibratory motion.

The abrasive tool is given the conformation substantially as shown in Fig. 4. It is preferably composed of two blocks, 20, a corner-pad, 22, and tang 24, all of which are united, as shown in Fig. 5. The central block, 26, is composed of felt. The tang 24 is cast with a

disk, 23, on one end, and is secured to the block 26 by bolts 21, that pass from the block up through the disk 23, as shown in Fig. 5. The ends of block 20 are composed of rubber. 5 They are secured to the central block by means of glue, and they are each provided with a horizontal groove, 27. Said grooves are intended to receive narrow strips or tongues, which have one end hinged to the block, so as 10 to swing outward, as shown in Fig. 5, and are provided with brads on the inner side, which pierce the abrasive material as the tongue goes into the groove, so as to strain and draw the material about the tool, as referred to herein-after. The tongue, when pressed fully into the groove, is locked therein by a spring-bolt, 40, which slides over the end of the tongue in an obvious manner, and prevents the tongue from swinging outward till the said catch-bolt 20 is moved back. The pad 22 is composed of felt or a similar flexible substance softer than the central block, 26. It practically covers the entire bottom surface of the foot, being attached thereto by means of glue. It is convex on its bottom face, and forms a soft yielding backing for the abrasive brush. This brush consists of a piece of cloth or other fibrous material, covered on its under side with fine emery, or with glass or other equivalent abrasive material. 25 It is placed on the foot with its back in contact with the pad 22, its edges being drawn up around the foot, so as to stretch and fit it closely to the pad 22, whereupon the tongues 25 are pressed into the groove 27, 30 so as thereby to force the edges of the cloth into the groove 27 and hold it strained tightly about pad till worn out by use, when it is removed and a new piece substituted for it.

In one class of sole-cleaning machines the 40 abrasive tool is an annulus or disk, which is revolved continuously in only one direction. In another class of machines the abrasive tool is an endless belt, which is also moved continuously in only one direction.

In my invention the abrasive tool is given 45 a vibratory motion, so that any fibers which escape the movement of the tool in one direction must certainly yield to the movement thereof in the reverse direction. This vibratory movement of the abrasive tool is a much 50 closer imitation of the movements of the human hand, and it enables the tool to cut the fibers of the leather much closer, and thereby brings out the finest texture of the leather, so as to give the sole a hard solid finish. This 55 finish may be greatly enhanced by the introduction of a hard-finish brush into my machine. This brush is also preferably given a vibratory movement, as before described.

Having thus described my invention, what I 60 claim is—

1. The combination of the disk 6, the connecting-rod 14, the crank 15, and the abrading-tool attached to the crank, having a vibratory movement in opposite directions, substantially as described.

2. A machine for abrading and finishing the soles of boots and shoes, consisting essentially of a supporting-column, an abrading-tool having a vibratory motion, a revolving 70 cleaning-brush and reciprocating hard-finishing brush, and an exhaust-fan and draft-passage for conveying and discharging the dust, all substantially as described.

3. An abrading-tool consisting of the felt-block 26, having a tang, by which it is secured to the under side thereof, the block 20 on the end, and the projections 25, adapted to close with grooves 27 in the end block, all substantially as described.

In testimony whereof I have signed this specification.

GEORGE W. COFFIN.

In presence of—

WILLIAM T. GRAY,
C. B. TUTTLE.
